LOUIS TAKACS, OF BRIDGEPORT, CONNECTICUT.

DAMPER-REGULATING MECHANISM FOR FURNACES.

1,318,118.

Specification of Letters Patent.

Patented Oct. 7, 1919.

Application filed February 3, 1919. Serial No. 274,621.

To all whom it may concern:

Be it known that I, LOUIS TAKACS, a citizen of the Republic of Hungary, residing at Bridgeport, county of Fairfield, State of Connecticut, have invented an Improvement 5 in Damper-Regulating Mechanism for Furnaces, of which the following is a specification.

This invention has for its object to provide 10 regulating mechanism for the flue dampers of furnaces, that will effect an important saving in fuel, that will enable the operator to regulate the draft at will by means of the flue damper independently of 15 the operation of the coaling doors, and which shall be so constructed and arranged as to make it impossible to open the coaling doors without closing the flue damper, thus wholly obviating the danger of a back draft 20 and a burst of flame and gas when the coaling doors are opened, and furthermore assuring a maintenance of the thermal efficiency of the boiler during the operation of coaling, as the inrush of a volume of cold 25 air and the consequent cooling of the boiler tubes and the walls of the furnace is prevented.

With these and other objects in view I have devised the novel damper regulator 30 which I will now describe referring to the accompanying drawing forming a part of this specification and using reference characters to indicate the several parts.

Figure 1 is a perspective view, of a furnace, partly broken away, showing the application thereto of my novel damper regulator, the coaling doors being closed and the regulator having been operated to lock the doors and open the flue damper, and

40 Fig. 2 is a similar view, the regulator having been operated to close the flue damper and one of the coaling doors being opened.

10 denotes a furnace which may be of any ordinary or preferred type, 11 the coaling doors, 12 the ash pit doors, and 13 the flue damper, which is rigidly secured to a shaft 14 one end of which extends through the wall of the furnace and is provided with an arm 15. 16 denotes a regulating 45 shaft which is mounted to oscillate in bearings 17, secured to the front of the furnace above the coaling doors. This shaft is provided with an operating handle 18, for convenience in manipulation, and 50 with locking arms 19, which are suitably shaped to engage the coaling doors when

closed and lock them in the closed position until the shaft is operated. I have shown these arms as bent to angular form and provided with contact plates 20 which lie flat against the faces of the coaling doors in the closed position. One end of the shaft 16 extends outward beyond the side of the furnace and has rigidly secured thereto one or more pulleys of different sizes, indicated by 21. 22 denotes a weight attached to a cable 23, the other end of which is connected to one of the pulleys, passing partly around the periphery thereof. These pulleys also have connected to them other cables, indicated 55 respectively by 24 and 24¹ having at their free ends respectively hooks 25 and 25¹. One of these hooks is connected to a ring at the end of a cable 26 which passes over guide pulleys 27 and is connected to arm 15 on the 60 damper shaft. From this arm the cable extends over another pulley 27 and carries at its end a weight 28. Weights 28 and 22 65 act as a counter-balance and cause the regulator to work easily.

The operation will be obvious from the drawing. When the coaling doors are closed, as in Fig. 1, and the locking arms are placed in engagement therewith by oscillation of shaft 16, the damper will be in the 70 open position and it will be impossible to open the coaling doors without first independently oscillating the shaft by means of handle 18, the effect of which will be to partly or wholly close the damper. If the 75 shaft is turned backward far enough to throw the locking arms to their extreme position, as in Fig. 2, the damper will be wholly closed, as shown. If the shaft is turned only far enough so that the doors in 80 opening can clear the locking arms, then the damper will be only partly closed, for example seventy-five per cent. closed. Should the general conditions of draft, etc., be such 85 that it is preferable not to wholly close the damper, the cable attached to the larger pulley may be disconnected from cable 26 and the cable attached to the smaller pulley may be connected to cable 26, the effect of 90 which would be to impart less closing movement to the damper. It will readily be seen that whether the damper is wholly or partly closed when the locking arms are at their 95 locking position, as in Fig. 1, is merely a matter of adjustment, the conditions of 100 course varying with different furnaces. The 105 important feature of the invention is that 110

while the damper may be regulated to suit conditions when the coaling doors are closed, the coaling doors cannot be opened without either partly or wholly closing the damper 5 as may be found most effective. In coaling one of the coaling doors only should be opened at a time. I have found in practice that the use of this regulator effects an important saving in the amount of fuel required to maintain the thermal efficiency of 10 the boiler.

Having thus described my invention, I claim:

1. In a draft regulating mechanism for 15 furnaces, the combination with a flue damper, of an oscillatory regulating shaft provided with means for locking the furnace door in closed position, means by which said shaft may be oscillated, and a 20 positive connection between the damper and the regulating shaft, whereby movement of said shaft actuates the damper, said door locking means and said damper being so related that the furnace door cannot be 25 opened until the damper has first been shifted from the position normally occupied when the door is closed.

2. In a draft regulating mechanism for 30 furnaces, the combination with a flue damper, of an oscillatory regulating shaft, locking arms projecting from said shaft and having door engaging portions for 35 locking the furnace doors in closed position, means by which said shaft may be oscillated, and a positive connection between the damper and the regulating shaft, whereby movement of said shaft actuates the damper, said door locking means and said damper being so related that the furnace 40 doors cannot be opened until the damper has first been shifted from the position normally occupied when the door is closed.

3. In a draft regulating mechanism for 45 furnaces, the combination with a flue damper, of an oscillatory regulating shaft, an angular arm projecting from said shaft and provided at its free end with a door engaging portion for locking the furnace 50 door in closed position, means by which said shaft may be oscillated, and a positive connection between the damper and the regulating shaft, whereby movement of said shaft actuates the damper, said door locking means and said damper being so related that the furnace doors cannot be opened 55 until the damper has first been shifted from the position normally occupied when the door is closed.

4. In a draft regulating mechanism for 60 furnaces, the combination with a flue damper, of an oscillatory regulating shaft provided with means for locking the furnace door in closed position, a pulley carried by said shaft, means by which said shaft may be oscillated, a cable connection between the pulley and the damper, whereby movement of the shaft actuates the damper, said door locking means and said damper being so related that the furnace 65 door cannot be opened until the damper has first been shifted from the position normally occupied when the door is closed, and counterbalance weights coöperating with said cable connections.

5. In a draft regulating mechanism for 70 furnaces, the combination with a flue damper mounted upon a shaft provided with an operating arm, of an oscillatory regulating shaft provided with means for 75 locking the furnace door in closed position, means by which said shaft may be oscillated, a pulley secured to said regulating shaft, a cable attached to said pulley and passing partly around it, a weight attached 80 to said cable, a cable connection between said pulley and said damper operating arm, and a weight attached to the cable connection, said door locking means and said damper being so related that the furnace 85 door cannot be opened until the damper has first been shifted from the position normally occupied when the door is closed.

6. In a draft regulating mechanism for 90 furnaces, the combination with a damper, 95 of an oscillatory regulating shaft provided with a pulley on one end, means by which the shaft may be oscillated, a cable passed partially around said pulley and having one end attached thereto, a weight attached 100 to the other end of said cable, a second cable attached to said pulley, means for connecting the second cable to the damper, and means for counterbalancing the damper.

7. In a draft regulating mechanism for 105 furnaces, the combination with a damper, of an oscillatory regulating shaft provided at one end with pulleys of different sizes, means by which the shaft may be oscillated, a cable passed partially around one of said 110 pulleys and having one end attached thereto, additional cables attached to the respective pulleys, a weight attached to the first mentioned cable and means whereby either additional cable may be connected 115 with the damper.

In testimony whereof I affix my signature.
LOUIS TAKACS.
